UNITED STATES PATENT OFFICE

2,506,481

CRAVAT HOLDER

Joseph Carlton Bagnall, Jr., Attleboro, Mass., assignor to Swank, Inc., a corporation of Delaware

Application November 28, 1947, Serial No. 788,400

2 Claims. (Cl. 24—49)

1

This invention relates to a cravat holder which will retain the cravat in position in front of the shirt.

Cravat holders which are provided of this general type are usually of fixed width, but if adjustable are of a relatively complicated construction.

One of the objects of this invention is to provide a cravat holder which may be adjustable so that various widths of cravats may be utilized and which will be of a relatively simple construction.

Another object of this invention is to provide a cravat holder which will engage the opposite edges of the cravat and which will so grip the opposite edges that they will be retained firmly in the cravat.

Another object of this invention is to provide two unit parts which may be relatively moved for adjustment to the size of the cravat holder.

With these and other objects in view, the invention consists of certain novel features of construction, as will be more fully described and particularly pointed out in the appended claims.

In the accompanying drawings:

Figure 1 is a top plan view of the cravat holder.

Figure 2 is a side elevation thereof illustrating in dotted lines the position of the cravat therein.

Figure 3 is a sectional view thru the center of the cravat holder.

Figure 4 is an exploded perspective view of one of the members.

Figure 5 is a perspective view of the other member of the holder.

In proceeding with this invention, I provide two members which will be so constructed that at one end each will embrace the edges of the cravat, while at their opposite ends the members will overlie one another, with a guide provided on one member to embrace the other member so that the members may relatively slide lengthwise to adjust the position of the embracing ends of the members to accommodate cravats of varying widths.

With reference to the drawings, 10 designates generally one member (Fig. 5), and 11 the other member (Fig. 4) of the cravat holder. Member 10 comprises a piece of sheet stock 12, which is bent upwardly at one end as at 13 and on this upwardly bent end there is an arm 14 which extends generally in spaced relation to the body portion 12, and inclines slightly toward the body at its inner end 15.

At the opposite end of this member there are

yokes 16 and 17 providing a pair of guides which are in the form of an inverted U shape piece secured to the outer edge of the member as illustrated in Figure 5. At this end of the member there is a cut out portion 18 which leaves a pair of legs 19 and 20 for a function which will be presently described.

The other member 11 of the cravat holder comprises a body portion 21 which has one end bent as at 22 to which there is attached an arm 23 to extend generally in spaced relation to the body 21, inclining slightly toward the body at its inner end, for receiving the edge of the cravat therein.

15 A tongue 24 is formed from the body 21 by slitting the stock thereof along parallel spaced lines and bending the portion between the slits as at 25 from this body portion so as to leave legs 26 and 27.

20 These legs will pass thru the guides 16 and 17 to be slideably embraced thereby as shown in Figures 1 to 3 and a stop 28 will be secured on the ends of the legs 26 and 27 so that this stop would engage the guide 17 to limit the outward 25 movement of the members. The tongue 24 will be received in the space 18 between the legs 19 and 20 of member 10 as the members are moved into contracted position so that the tongue will not interfere with this movement of the members.

30 When in contracted, or partially contracted position, such as shown in Figure 2, the arm 14 will be sufficiently close to stop 28 so as to bind the cravat, as shown at 30, between the arm and 35 the stop 28, while at the other end, the cravat will be bound between the guides 16 and 17 and the arm 23 so as to hold the cravat securely in position.

35 By this arrangement cravats of varying widths 40 may be nicely accommodated by adjusting the holder so as to match the width of the cravat and when the cravat is in position it will be held by being bound as above described. Alternatively, the cravat holder may be placed at an expanded position and moved toward contracted 45 position by pressure upon the ends of the holder until the desired size is acquired.

I claim:

1. A cravat holder comprising a pair of members, each having means at one end to engage the edge of a cravat, one member being provided with guiding means and the other member slideably guided in said means whereby said members may be moved relatively to adjustably 55 space their cravat edge engaging means for ac-

commodating different widths of cravat, and a tongue to grip the shirt deflected from the center of one of said members and the other one of said members provided with spaced legs to receive between them said tongue as the members are slidably moved to contracted position. 5

2. A cravat holder comprising a pair of members, each having means at one end to engage the edge of a cravat, one member being provided with guiding means and the other member slidably guided in said means whereby said members may be moved relatively to adjustably space their cravat edge engaging means for accommodating different widths of cravat, one of said members comprising an overhanging arm to extend inwardly from an edge of the cravat and the ends of the other member underlying said overhanging arm and being turned toward said arm in close proximity thereto to bind the cravat between them. 20
